UNITED STATES PATENT OFFICE

CARL R. YOUNG, OF SAPULPA, OKLAHOMA, ASSIGNOR TO BARTLETT-COLLINS COMPANY, OF SAPULPA, OKLAHOMA, A CORPORATION OF OKLAHOMA

DESIGN FOR A COMBINATION RECEPTACLE AND SMOKER'S SET

Application filed March 13, 1931. Serial No. 39,076. Term of patent 14 years.

To all whom it may concern:

Be it known that I, CARL R. YOUNG, a citizen of the United States, residing at Sapulpa, Creek County, in the State of Oklahoma, have invented a new, original, and ornamental Design for a Combination Receptacle and Smoker's Set, of which the following is a specification, reference being had to the accompanying drawing forming a part thereof, and in which the figure is a perspective view of the article.

I claim:

The ornamental design for a combination receptacle and smoker's set substantially as shown.

In witness whereof, I have hereunto set my hand.

CARL R. YOUNG.
